PORTABLE BIRD BATH

Katherine K. Mitchell, Box 81, Rancho Santa Fe, Calif.

Filed Aug. 2, 1965, Ser. No. 86,408

Term of patent 14 years

(Cl. D31—2)

FIG. 1.

FIG. 2.

FIGURE 1 is a perspective view of a portable bird bath showing my new design, the side opposite being similar in appearance; and,

FIGURE 2 is a sectional view of the bowl and water spout to an enlarged scale, the plane of the section being taken on a diameter of the bowl.

I claim:

The ornamental design for a portable bird bath, as shown and described.
